AIR CONDITIONING SYSTEM

Kemper P. Brace and Robert B. P. Crawford,
Washington, D. C.

Application January 21, 1935, Serial No. 2,826

8 Claims. (Cl. 98—33)

This invention deals with the art of air conditioning. Its primary object is to provide a simple, inexpensive and efficient method of maintaining positive individual temperature and humidity regulation in the various rooms of buildings such as hotels, apartment buildings and office buildings wherein the rooms on each floor open into or are located adjacent a common corridor or passageway.

10 Heretofore attempts have been made to effect the above results in several different ways, one of these being to run individual conditioned air supply and return ducts to each room, the outlets of which ducts are thermostatically adjustable to supply the proper amount of air to maintain the desired condition in each room. In addition to its high installation cost, this system has the disadvantage of instability of regulation because the operation of each thermostatically controlled damper has a pronounced effect upon the air flow from every other dampered outlet. Furthermore the opening of windows in any one room interferes with the adjustment of the entire system.

25 To obviate the above disadvantages, systems have been designed which provide for an individual, automatically controlled conditioning unit in each room. There are many modifications of this so called unit system. In some cases all 30 the functions of cooling, heating, humidifying, dehumidifying, filtering and circulation of air are performed within the individual units. In other instances, the units are used merely to heat or cool and circulate the air, the remaining functions being accomplished by a central system 35 which supplies a relatively small amount of air having the proper moisture content to the corridors of each room, this air being allowed to diffuse into the individual rooms for proper humidity control.

40 Although the operation of the unit type of system is not entirely unsatisfactory, the installation cost is extremely high due to the high cost of units, electric wiring, water, refrigerant and drain piping, pipe covering, etc.

The proposed new system forming the subject matter of this application provides the advantageous operating characteristics of the unit system at an extremely low first cost.

50 Further objects and advantages will become apparent from the description which follows.

Referring to the accompanying drawings which are made a part hereof and on which the same reference characters are used to describe the 55 same parts throughout.

Figure 1 is a view in elevation with parts in section showing my invention.

Figure 2 is a section on line 2—2 of Figure 1.

Figure 3 is a section substantially on line 3—3 of Figure 2.

Figure 4 is an enlarged detail showing control of air circulating fan, and

Figure 5 is a detail showing control of air from the ducts to corridors.

10 In the drawings numeral 10 indicates the outside walls of a building which may be divided by partitions 11 into rooms 12 and corridors 13. The corridors are connected by means of doors 14 with the rooms. Numerals 15 and 16 indicate conventional elevators and stairways which may 15 open into the corridors 13. Air supply shafts 17 and air return shafts 18 extend from the basement of the building to the topmost corridor. In each corridor and near the ceiling are positioned air supply ducts 19 to conduct the air 20 from the shafts 17 into the corridors at a relatively high velocity and in such a manner that thorough mixing of the supplied air and the air already in the corridor is accomplished almost 25 instantaneously. Air supplied to the shafts 17 is drawn through an air treating unit 20 by a fan 21. This treating unit may be a humidifying and heating system for winter use and a dehumidifying and cooling unit in summer.

30 For cooling and dehumidifying the air, the unit 20 may be any suitable mechanical refrigerator to cool and dehumidify a relatively small quantity of air and supply the same to the corridors at a relatively low temperature through the high velocity ducts 19 to effect rapid mixing. The 35 cooling in the unit 20 may be effected by cold water sprays, by direct expansion or by cold water passing through radiators having finned coils. Instead of cooling a small quantity of air to a low temperature the mechanical refrigerator may 40 be arranged to cool and dehumidify a relatively large amount of air and supply it to the corridors at a relatively high temperature at low velocity. This system requires an interchange of 45 heat between the hot air entering the central cooling system 20 and the cold air leaving the system for raising the temperature of the entering air. The cooling in this case may also be by cold water sprays, by direct expansion or by cold water circulating through finned coils.

50 Refrigeration in the unit 20 may also be by adiabatic chemical dehumidification followed by recooling with suitable cooling means, such, for example, as artesian well water or mechanical refrigeration.

Isothermal dehumidification may be used in which the dehydrating medium is cooled by suitable means such as artesian well water, by mechanical refrigeration or in any other suitable way.

- 5 Dampers 22 controlled by motors 30 regulate the amount of air delivered to the corridors. These motors are controlled by thermostats 23 in the corridors. By means of these thermostatically controlled dampers it is possible to maintain 10 the corridors at any predetermined temperature under varying load conditions. For economy of operation air is returned through openings 24 from the corridors to the return air shafts 18 through which it returns to the conditioning system 20.

Located in openings 25 in the partitions 11 between the rooms 12 and the corridors 13 are fan units 26. The purpose of these fans of course is to draw air from the corridors and supply it to 20 the rooms as needed to maintain the rooms at the proper temperature condition. The fans are operated by motors 31 controlled by thermostats 27 located in the rooms into which the fans are delivering the air. The doors of the rooms are provided with grills 28 or other openings near the floor to allow the air to return to the corridors.

The operation of the system is as follows:

All of the corridors are maintained at a constant humidity and temperature condition. This 30 may be at a higher or lower temperature than that desired in the rooms depending on whether the rooms are to be heated or cooled. During the summer months when the building is to be cooled, the corridors are maintained automatically at a temperature about five degrees cooler than the temperature desired in the rooms. In summer it will be desirable to keep the temperature in the rooms about 85° F. The temperature in the corridors will be kept at about 80° F., the 40 thermostats 27 and 23 being set to keep the rooms and the corridors at the respective desired temperatures. If the temperature in the rooms rises above a predetermined degree the fans are set in operation. Since each fan unit is equipped 45 with its own controlling thermostat different temperatures may be maintained in the different rooms, by a simple setting of the thermostat. Since each fan runs at a constant speed it will deliver a constant volume of air. Upon opening 50 a window in any room, there will be no interference with other rooms and no material disturbance with air conditions in the corridors.

During the winter months the corridors will be maintained at about 84° to maintain a temperature of about 75° F. in the rooms.

It will be obvious to those skilled in the art to which this invention pertains that various changes may be made in the invention without departing from the spirit thereof, we therefore 60 do not limit ourselves to the specific showing and description but only to the invention as set forth in the claims.

What we claim therefore is:

1. In a building having a corridor and a plurality of rooms opening into said corridor, an air shaft, an air conditioning system for supplying air having a predetermined temperature and humidity to said shaft, thermostatically controlled means for supplying air at high velocity 70 to said corridor from said shaft, separate means for supplying air from said corridor to said rooms and heat responsive means in each of said rooms in control of each of said air supplying means.

2. In a building having a plurality of rooms 75 and a corridor connected with said rooms, an air

conditioning system, an air shaft having a restricted opening into the corridor for supplying air at high velocity from said system to said corridor, means responsive to air conditions in said corridor for controlling the volume of air supplied to said corridor, means for supplying air from said corridor to said rooms and means responsive to air conditions in said rooms for controlling the supplying of air to said rooms.

3. In a building having a plurality of rooms 10 and corridors, air passages connecting said rooms with said corridors, means in said passages for forcibly supplying air from said corridors to said rooms, individual heat responsive means in each of said rooms for controlling the volume of air 15 supplied to each room, an air shaft means for conditioning and supplying conditioned air to said air shaft, said air shaft being connected thru restricted openings with said corridors thru which air is supplied at high velocity from said shaft to 20 said corridors and heat responsive means for controlling the volume of conditioned air supplied from said shaft to said corridors.

4. In a building having a plurality of rooms on each floor and a common corridor on each floor 25 having passages connecting it with each room said passages including an air supplying and an air return passage, means in said air supplying passage for forcibly delivering air at a constant rate to said room heat responsive means in each 30 of said rooms for controlling said air supplying means and means responsive to air conditions in said corridors for supplying air at high velocity to said corridors for maintaining the air therein at a constant temperature and humidity condition. 35

5. In a building having a plurality of rooms and a corridor common to said rooms, a grill adjacent the top of each room and opening into the corridor for supplying air from the corridor 40 to the room, an opening adjacent the bottom of each room for returning air from the room to the corridor, fans in said upper openings for forcibly supplying air from said corridors to said rooms, heat responsive means in said rooms in control of 45 said fans, a central air conditioning system, an air duct for supplying air from said system to said corridors, a plurality of dampers for controlling the volume of conditioned air delivered from said duct to said corridors, heat responsive 50 means in said corridors for controlling said dampers, a duct for returning air from said corridors to said system.

6. The method of cooling a building having a plurality of corridors and a plurality of rooms 55 communicating with each corridor which comprises agitating the air in each corridor and maintaining it at a predetermined temperature lower than that desired in the rooms, forcibly delivering air from said corridors to said rooms 60 and controlling the volume of air so delivered in response to the dry bulb temperature in said rooms.

7. An air conditioning system for a building having a plurality of rooms at different levels 65 a corridor connecting all of the rooms on one level an air conditioning unit having means for maintaining air at a predetermined temperature and humidity, vertical air shafts for conducting air to and from said air conditioning unit and 70 said corridor, restricted openings from one of said shafts for conducting conditioned air at a relatively high velocity from said shaft into said corridors to mix the incoming air with that in the corridors, and a plurality of rooms having 75

openings for admitting air from said corridors into the rooms.

8. An air conditioning system comprising a corridor having openings for supplying conditioned air to and for withdrawing air from rooms to be conditioned, an air supplying shaft and an air return shaft for supplying air to and for withdrawing air from said corridor, an air conditioning unit thru which air is caused to pass 5 from the return to the air supplying shaft, a restricted opening from said air supplying shaft to said corridor for adding velocity to the air as it enters the said corridor to agitate the air therein and thereby mix the incoming air with the air already in the corridor and thermostatic means responsive to the temperature in the corridor for controlling the said restriction. 10
